(57) CLAIM

The ornamental design for a needle-less injector, as shown and described.

DESCRIPTION

FIG. 1 is a perspective view of a needle-less injector showing my new design.

FIG. 2 is a front elevational view thereof, the rear elevational view being identical thereto.

FIG. 3 is a right side elevational view thereof, the left side elevational view being identical thereto.

FIG. 4 is a bottom end view thereof.

FIG. 5 is a top end view thereof; and,

FIG. 6 is a perspective view thereof, with the end cap and safety clamp shown in broken line and forms no part of the claimed design invention.

1 Claim, 3 Drawing Sheets

FIG. 1

FIG. 6
